UNITED STATES PATENT OFFICE.

VICTOR PETERSON, OF DOWNSERS GROVE, ILLINOIS.

PROCESS OF MAKING MULTICOLOR PRINTS.

962,718.

Specification of Letters Patent. Patented June 28, 1910.

Application filed June 4, 1908. Serial No. 436,538.

To all whom it may concern:

Be it known that I, VICTOR PETERSON, a citizen of the United States, residing at Downers Grove, in the county of DuPage and State of Illinois, have invented certain new and useful Improvements in Processes of Making Multicolor Prints, of which the following is a specification.

This invention relates to an improved process of making multi-color prints, the printing being done by a succession of impressions and being analogous to the so-called four-color process.

The salient object of the present invention is to provide a process whereby a subject may be printed in a plurality of colors, properly distributed and blended, without the necessity of providing different special printing plates for each color.

Other objects of the invention are to provide a process which renders less essential extreme accuracy of register; to provide a process which eliminates much of the technical and artistic skill, experience and judgment necessarily involved in successfully carrying out the so-called tri-color or four-color processes; to provide a process which is more rapid as a whole; to provide a process which is capable of being carried out by extremely simple appliances, in ordinary printing establishments and at a very substantial saving in cost as compared with the tri-color or four-color processes, and which in this way opens up a much wider field of application; and in general to provide an improved process of the character referred to.

To the above ends the invention consists in the matters hereinafter described, and more particularly pointed out in the appended claims.

The invention will be more readily understood by a description of a specific example of carrying it out; the description of such example being accompanied by drawings.

For illustration I have chosen a red rose arranged in a blue vase, the leaves and stem of the rose being green, and the shade and outline lines being black. Accordingly, Figure 1 illustrates the completed color-type print; Fig. 2 illustrates a relief tympan sheet, the relief portions of which effect the printing of those parts which are to appear in yellow and green; Fig. 3 is a second relief tympan sheet, the relief portions

of which effect those parts of the subject which are to appear in red; Fig. 4 is a relief tympan sheet, the relief portions of which effect the printing of those portions of the subject which are to appear in blue and green.

In carrying out the process I first prepare a suitable outline plate with just enough lines thereon to fix the color boundaries and I also prepare a key plate which may have outlines, dividing lines and shade lines which it is desired to have appear on the finished print. The outline plate is then set up on the press in the usual or any suitable manner. The platen or cylinder of the press is equipped with a suitable tympan sheet, and thereupon the pressman proceeds to print a plurality of sheets, say for example, a half dozen, so as to have a surplus, using paper which is suitable for use as tympan sheets and therefore preferably using the same kind of paper as that of the tympan first placed upon the press. These tympan sheets are preferably printed with ordinary black printers' ink, care being taken to apply the ink thoroughly but sparingly so as to secure clean-cut, sharp impressions. With the same make-ready the pressman runs off a plurality of impressions upon, what for convenience I will call overlay-stock sheets; these overlay-stock sheets being made of rather thick resilient paper, having, however, a dense, smooth surface, and of such character that it can be conveniently both cut into sections and readily peeled or scraped off in thin layers. In practice I find that paper of the character of the so-called enameled blotter stock, running about from 140 to 200 pounds to the ream, is suitable. This stock has the characteristics desired, and may be accurately cut into desired shapes by the use of an ordinary small pointed, sharp knife. Desirably also the pressman will run off a few impressions on any suitable paper, and desirably on the same stock which is to be used for the proposed job. These sheets I term register sheets and they are used simply for the purpose of helping the pressman secure register in preparing the several make-readys hereinafter described.

With the printed tympan sheets and printed overlay-stock sheets a set of relief-tympan-sheets is now prepared, one for each different color impression. These relief

110

tympons may be conveniently made as follows: The printer having determined what portions of the print are to appear in the different colors, usually by having a color scheme worked out in advance, proceeds to cut out from one or more of the overlay-stock sheets those portions of the impressions which are to appear in a given color, say yellow, and mounts these cut-out portions in exact register with, and upon the corresponding portions of the impression on one of the tympan sheets. Ordinarily, where there is considerable detail, in doing this he will first cut out from the overlay-stock the entire impression, transfer it to, fit it and paste it in exact register upon the impression on the tympan sheet. As soon as the paste or other adhesive is dry, he will then proceed to countersink, peel off, or cut out and remove from the overlay-stock thus pasted upon the tympan all those portions, except the areas which are to become the impression surfaces of the tympan. The impression surfaces will thus be left in relief. As to these relief surfaces, the printer or artist will peel off or scrape down such portions as are to appear less strongly in the finished impression, thus leaving the un-reduced surfaces to make the strongest impressions. Of course, the surfaces of the relief portions may be carved, dug or burned out, so as to produce stippled surfaces or other non-uniform surfaces, upon the printing areas, and the possibility of so treating these surfaces renders the process extremely flexible and capable of producing blending and shading effects. In this connection it will, of course, be understood that the intaglio portions of the tympan which are not to print may be removed as to the entire thickness of the overlay-stock or only a part of this thickness.

A set of relief tympons one for each color having been thus prepared, the outline plate is removed from the press and a plain plate is substituted. The tympan which was used for taking off the tympan sheet and overlay-stock sheet impressions is removed from the press and the relief tympan for the first color substituted upon the platen. This relief tympan is adjusted to register, and a strong but rather thin draw-sheet placed over it and secured in place. The press being now ready, I run the job through for the first impression or color. The press is then cleaned, the draw sheet released, the relief tympan removed, the tympan for the next color substituted and adjusted, and the job run through for the second impression or color. In the same way the other relief tympan sheets are applied and their colors printed, the printed sheets being then finished so far as the colors are concerned. The last used relief tympan sheet is now removed from the press and a plain tympan

sheet is substituted therefor, and the key plate is substituted for the plain plate. The colored sheets are now run through the press and the desired outlines, dividing lines or shade lines applied thereto by the key plate. Of course, if only the ordinary color boundary lines are to appear on the finished sheets the outline plate can be used for the final printing operation. Usually, however, more or less dividing and shade lines are desired to appear on the prints in addition to the main outlines, and key plates are, therefore, used for the final print.

Referring to the drawings Fig. 1 shows the finished print or subject, except only the half-tone or screen lines, which are so microscopical as to be incapable of proper illustration; the several parts of the print being shaded to indicate their respective colors. Fig. 2 shows the first relief tympan sheet in which the relief portions appear as shaded, yellow being indicated. The outline lines also appear upon the tympan but are of course not in relief. Fig. 3 shows the second relief tympan in which similarly the relief portions are shaded to indicate red. Fig. 4 shows the third tympan sheet in which the relief portions are shaded to indicate blue.

In the finished print the center of the flower appears in yellow, the petals red, the leaves and stem green (it being noted that the yellow and blue are superposed as to these portions) while the vase is blue, the outlines, dividing lines and shade lines being black.

For finer grades of work the plain plate associated with the relief tympan sheets, instead of being absolutely smooth, may have the usual screen lines of suitable mesh upon its face, and a different plate of this kind can be applied for each color impression by the tympan sheets, or the same plate can be re-adjusted on the press to change the angle or direction of the screen lines. Other modifications can also be made in my invention without departing from the spirit thereof.

I claim as my invention:

1. The improvement in the art of printing in colors, which consists in preparing a plurality of relief color tympons having their relief portions differently located thereon so as to apply the various colors on the proper place in a picture, equipping the bed of the press with a plain plate and the platen with one of said relief tympons and then running through the job for the first color impression, next removing said first relief tympan, substituting another relief tympan on the press and running through the job for the next color impression, finally removing the last used relief tympan and substituting on the press a plain tympan, removing the plain plate and substituting on the press a key plate and running

through the job for the final impression to receive outlines, dividing lines or shade lines.

2. The improvement in the art of color printing, which consists in first preparing an outline printing plate for printing the color boundaries, making ready the press with said outline plate and an opposed plain tympan, printing a plurality of sheets of over-lay stock and a plurality of sheets of tympan stock, cutting from each printed over-lay stock sheet that portion to be printed in a certain color, mounting said portion in its proper place on one of the tympan sheets, and so forming a relief tympan for said color, similarly forming a relief tympan for each different color, next equipping the bed of the press with a plain printing plate and the platen with one of said relief tympans, and running through the job for the first color impression, next removing the first used relief tympan and substituting a second relief tympan on the press and running through the job for the next color impression, repeating the operation of substituting tympans and running through the job for each color impression, and finally removing the last used relief tympan and substituting on the platen a plain tympan, removing from the bed the plain printing plate and substituting thereon a key plate and running through the job for the final impression to receive outlines, dividing lines, or shade lines.

3. The improvement in the art of print-

ing in colors which consists in building up upon different plain back sheets, relief portions corresponding to the parts of the impression which are to be printed in the several different colors, employing these relief tympans successively on the press, in opposition to and in conjunction with a plain printing plate, in printing the several color impressions, except the last, and making the last impression with a key plate and plain or non-relief tympan opposed thereto.

4. The improvement in the art of color printing which consists in preparing an outline plate of a picture to be printed, printing a plurality of tympan sheets with said plate, printing also a plurality of over-lay stock sheets with said plate, peeling off or countersinking portions of each over-lay sheet to leave relief portions for printing a certain color, then securing each over-lay sheet to a tympan sheet with the prints thereon in register, then removing the outline from the press and substituting a plain printing plate, then successively mounting the tympan sheets with the relief stock sheets thereon in the press, then successively applying to the printing plate the colors to be printed by the tympan sheets, and then successively printing the different colors to form the picture.

VICTOR PETERSON.
